UNITED STATES PATENT OFFICE.

THOMAS COWBURN, OF CHURCHDOWN, ENGLAND.

TOY HORSE PROPELLED BY THE RIDER.

1,418,626.

Specification of Letters Patent. Patented June 6, 1922.

Application filed August 25, 1920. Serial No. 406,035.

To all whom it may concern:

Be it known that I, THOMAS COWBURN, a subject of the King of Great Britain, residing at Apsley House, Churchdown, in the 5 county of Gloucester, England, have invented a new and useful Toy Horse Propelled by the Rider; of which the following is a specification.

This invention has reference to improvements in toy horses of the kind that are 10 propelled by the rider alternately rising in the stirrups and sitting down on the saddle and which forms the subject-matter of British Letters Patent granted to me under No. 15 113577.

A toy horse constructed substantially as described in the specification of the said Letters Patent, works quite satisfactorily if the rider steers a straight or nearly straight 20 course, but if he attempts to turn round a comparatively sharp corner it is found that one or other of the horse's legs is raised off the ground.

Although there is no real danger of the 25 horse and rider toppling over as the latter will maintain his normal position in such a situation, the mere appearance of want of balance or equilibrium is, in the minds of many, a serious defect, and it is the main 30 object of this my invention to obviate said defect.

My invention is illustrated diagrammatically in the accompanying drawing, Figs. 1 and 2 showing the toy horse in the extreme 35 positions that is to say in the former when the front and hind legs are apart to their full extent, brought about by the rider putting his weight on the saddle, and in the latter when said legs are brought nearest together, 40 brought about by the rider standing up in the stirrups.

Fig. 3 shows the complete horse and Figs. 4, 5, 6 and 7 details to be referred to.

To avoid having to refer to the specification of my said British Patent No. 113577 I include herein a description of the invention therein claimed. This consists of a toy horse made up of two main parts A, B, which are hinged together at the upper edges 45 and the hoofs of which are provided with rollers d which can only rotate in the forward direction. The part A has a bell-crank f, f', hingedly supported at e, the part A being made with a cavity to receive this. One 50 arm viz f' is connected by a chain or cord m to the part B, and the other arm f has

studs h projecting through slots in the part A and from which studs the stirrups s are suspended. If the rider sits down on the saddle and avoids pressing unduly on the 60 stirrups, the front legs D will move forward and when next he rises from the saddle so that his whole weight is on the stirrups the hind legs will be drawn forward. By thus intermittently transferring his weight alternately to the saddle and the stirrups the 65 horse is propelled forward.

My present invention consists in an important improvement in the connection of the parts A and B.

In the first place I fix to the front upper part of the part B, a plate r having a slot r' and at its front edge a depending boss t (Figs. 4 and 5). Connected to the boss by a pivot pin v are two webs or plates u' 75 that project from a vertical plate that has at its front face, at both side edges, vertical lugs u. The pivotal connection should be such that the webs u' can turn freely (to a desired extent) in the horizontal plane, relatively to the plate r, but the pivot pin v must not be too loose a fit in the boss t, so that rattling is avoided, and the boss should be of fair vertical length so that a too rapid 80 wearing of the pivot will be avoided.

Fixed to the rear upper portion of the part A is a plate w that has projecting from its rear edge a horizontal boss w' which fits snugly between the two lugs u to which it is pivotally connected by a pivot pin v'. 90 The aperture through the boss w' is made about as shown on a larger scale in Fig. 7, that is to say its centre part fits fairly snugly on the pivot pin v' whereas on each side thereof the aperture is made conical so that 95 in addition to the capacity to turn in the vertical plane relatively to each other, the parts w' and u' can to some extent rock or rotate relatively to each other.

By this means when the rider is turning 100 round a sharp corner the four rollers d will remain planted on the ground and the propelling forward, in the manner described, of the horse can be effected as easily as when a straight course is steered.

In order that the rider shall be quite comfortable when, as the result of his sitting down on the saddle, the parts A and B assume the position more or less as indicated in Fig. 1, I pivotally connect the saddle S at the 110 front end at p' to the part A and the rear end of the saddle or saddle-bar is provided

with a pin *p* which enters the slot *r'* in the plate *r* that is secured to the part *B*.

The saddle thus forms a sort of bridge, as will be understood from Figs. 1 and 2 of 5 the drawings, and affords a substantially horizontal seat, in all positions of the parts *A* and *B*, for the rider.

The pin and slot connection of the rear end 10 of the saddle and the plate *r* serves, in junction with the cord or chain *m*, to limit the extent to which the legs of the toy animal will spread apart when the rider puts his whole weight on the saddle.

The reins *R* are connected to the lower 15 ends of rocking spindles *n*, *n'*, which are carried at the ends of an imitation bridle and the upper ends of said rods are connected by cords *o'* to each side of the part *B* so that by pulling on either end of the reins 20 the horse will be steered.

I claim as my invention:—

1. In a toy horse adapted to be propelled by the rider putting his weight alternately on the saddle and stirrups, the combination 25 with a horse body having a front section and a rear section, a three-part hinge device connecting said sections, said hinge device having one member secured to the rear

section, one member secured to the front section, and an intermediate member hinged 30 to the first-named member to turn about a vertical axis and to the last-named member to turn about a horizontal axis, a lever pivoted to the front section and connected to the rear section, and stirrups connected to 35 said lever.

2. In a toy horse, the combination with a horse body having a front section and a rear section, of a three-part hinge device connecting said sections, said hinge device having 40 one member secured to the rear section, one member secured to the front section, and an intermediate member hinged to the first-named member to turn about a vertical axis and to the last-named member to turn about 45 a horizontal axis, said first-named member having a longitudinal slot, a saddle pivoted at its front end to the first section and having a pin operating in said slot, a bell crank lever pivoted to the front section and connected to the rear section and stirrups hung from said lever.

THOMAS COWBURN.
